UNITED STATES PATENT OFFICE.

HARRY D. BINKS, OF OAK PARK, ILLINOIS, ASSIGNOR, BY MESNE ASSIGNMENTS, TO BINKS MANUFACTURING COMPANY, OF CHICAGO, ILLINOIS, A CORPORATION OF DELAWARE.

PAINT SPRAY NOZZLE.

Application filed October 9, 1924. Serial No. 742,549.

My invention relates to appliances for distributing liquids in the form of a sheet of spray, and more particularly to a head construction for such an appliance.

- 5 In using spraying appliances of this class for distributing paints, varnishes or the like over the surfaces of objects which are to be coated with the initially liquid material, it is customary to employ socalled "spray guns" 10 in which the liquid is projected in the form of a relatively flat sheet and in which the general plane of that sheet can readily be shifted. However, such appliances, as heretofore in use, have proven inadequate for 15 spreading the sprayed material with the desired uniformity over the surface which is to be coated. This is due partly to an insufficiently fine atomization of the liquid, which in itself would tend to produce a coating of irregular density. It also appears to be due to the projecting of certain portions of the resulting spray at a velocity greatly in excess of that at which other portions are projected, thereby producing the socalled 20 "pock marks" which seriously mar the appearance of the resulting coating.
- My present invention aims to overcome all of the above named objections while providing a simple, easily manipulated and 25 easily cleaned nozzle head construction which will be equally adapted for producing a substantially flat spray in either of two general planes or for producing a round spray. More particularly, my invention aims to provide a 30 nozzle head construction which will afford an unusually fine atomization of the liquid, and one which will reduce the velocity of the spray-flattening and spray-atomizing jets of air so as to avoid the formation of such undesirable "pock marks." More particularly, 35 my invention aims to provide a nozzle head construction in which a projected stream of liquid is initially housed by a tubular stream of compressed air, and in which this liquid stream is atomized and deformed into a substantially flat spray by a plurality of streams of air directed in forwardly converging relation to the stream of liquid from opposite sides of the general plane along which the 40 spray is to be flattened. Furthermore, my invention provides an exceedingly simple and easily cleaned head construction for this purpose, which will readily permit the plane of the flattened spray to be shifted from one to 45

another of two planes at right angles to each other, and which will afford an unflattened or conically diverging solid spray when a rotatable portion of the nozzle head is disposed in an intermediate position. It also provides a spray or head construction for 50 this purpose in which the spray-varying member is continuously spring-pressed into properly fitting relation to the collar which holds this member in position, and in which the said member can readily be removed 55 without the use of tools to permit any needed cleaning of its parts. Still further and also more detailed objects will appear from the following specification and from the accompanying drawings, in which 60

Fig. 1 is a side elevation of a spray gun embodying my invention, showing this as adjusted for projecting a spray flattened in the same medial plane with the laterally flattened handle. 70

Fig. 2 is a fragmentary and enlarged central and longitudinal section through the same spray gun. 75

Fig. 3 is a front elevation of the head of the spray gun, taken from the left hand end 80 of Fig. 2, with dotted lines showing the position of the spray-flattened member when disposed for flattening the spray in a horizontal plane.

Fig. 4 is a front elevation of the head with 85 the holding collar removed.

Fig. 5 is a front elevation of the head with both the spray-flattening member and the holding collar removed.

Fig. 6 is a perspective view of the spray- 90 flattening member with dotted lines showing the directions of the converging streams of compressed air.

Fig. 7 is an elevation of the spray-flattening member, taken from the bottom of Fig. 4. 95

Fig. 8 is an enlarged longitudinal section of a portion of the head, showing the spring-pressed plunger construction employed for latching the spray-flattening member in any adjusted position, taken along the line 8-8 100 of Fig. 5.

Fig. 9 is a rear elevation of the collar of the head, showing the recesses which form air ports.

Fig. 10 is a diagram showing the relative 105 directions of the spray-flattening air jets with respect to the plane along which the spray is to be flattened.

In the embodiment of the drawings, the spray gun of my invention comprises a body member 1 having a horizontal portion provided with a longitudinal bore 2 to which the 5 paint or other liquid is admitted through a vertical bore 3 from any supply of liquid connected by a hose 4 to the lower end of this inlet bore 3. Threaded into the forward end of the bore 2 is a nozzle core 5 which has a 10 longitudinal bore 6 controlled by a needle valve 7. The stem of the needle valve is continuously urged forward by a compression spring 8 but can be drawn rearwardly by rearward pressure on a trigger lever 9 which 15 is connected to the said stem by a link 10, for which purpose the connection between the link 10 and the stem of the needle valve desirably includes a pair of portions 11 and 12 threaded upon each other so as to be adjustable to vary the relative position of the valve 20 stem with respect to the lever 9.

The body member 1 also includes a hollow handle member 13 which has an air inlet tube 14 extending upwardly into it and leading 25 to a transverse bore 15 which bore connects the said air inlet tube 14 to an air duct 16 having a pair of outlets 17 at the forward end of the body member. The connection between the air inlet pipe 14 and the air duct 30 16 is controlled by a valve 18 which is continuously urged forward by a spring 19 and which has a forwardly projecting stem 20 engaging the rear face of the trigger lever 9.

The nozzle core 5 desirably tapers forwardly as shown in Fig. 2 and terminates in a cylindrical portion which extends into the central aperture 21 of a spray-flattening member 22, the aperture 21 being sufficiently larger in diameter than the forward end portion of 40 the nozzle core to permit a hollow stream of compressed air to issue through the said space. When thus issuing, this hollow stream of compressed air laterally houses the stream of liquid issuing through the axial bore 23 of the nozzle core (or the bore controlled by 45 the needle valve 7) so as to prevent a material spreading of this liquid stream until the latter is engaged by the converging air jets hereafter described.

50 In addition to the axial aperture or liquid outlet 23 of the nozzle core, the spray-flattening member 22 has a plurality of air ports arranged so that their axes converge after the manner of the edges of a flattened pyramid 55 toward the axis 24 of the aperture 21, whereby air jets issuing from these ports will intersect at a common point on the stream of liquid issuing from the said liquid outlet 23. To insure an accurate directing of the converging 60 air jets for this purpose, I preferably make the corresponding ports (25, 26, 27, 28) of a considerable length and preferably dispose their outlet ends forwardly of the outlet ends 65 of the liquid outlet 23 and of the annular air outlet 21. For this purpose, I provide the

member 22 with a pair of forwardly projecting lugs 29 and 30 through which the said four ports extend, and preferably provide these lugs with forward face portions approximately at right angles to the said ports. 70 Then I provide the member 22 with a pair of lateral recesses affording inlets respectively to the two pairs of angular ports after the manner shown in Fig. 7.

To supply the needed compressed air to 75 these ports, I support the member 22 so that its rear end is freely spaced from the forward end of the body member, thereby providing an air chamber into which the air outlets 17 open. This chamber is laterally 80 bounded by a holding collar 33 which is threaded on the forward end of the body member and which preferably has a bore corresponding in forward taper to the exterior of the member 22, so as to house the 85 latter snugly. Then I provide the bore of the collar with longitudinal recesses through which air can pass alongside the member 22 to the lateral recesses 31 and 32 respectively. The said longitudinal recesses are preferably 90 arranged in two pairs with the recesses of each pair diametrically opposite each other and with the corresponding diameters at right angles to each other. Thus arranged, it will be evident that when the member 22 is in 95 the position of Figs. 1, 2 and 3, air will reach the converging ports in this member through the passages or recesses 34; and that with the member 22 in the position indicated in dotted lines in Fig. 3, air will reach these ports through the recesses 35. To hold the member 22 in either position while still permitting it to be rotated instantly from one position to the other, I provide spring means continuously pressing the member 22 against the 100 holding collar 33, such as plungers 36 extending slidably through tubular guides 37 threaded into the forward end of the body member, each plunger being pressed forwardly by a spring 38.

105 While the directions of the converging air jets may be varied somewhat, those issuing from each of the two lugs on the member 22 preferably are disposed at sharply acute angles towards each other, as shown in Fig. 110 10 by the angles 39 and 40 respectively. Thus arranged, each such pair of jets tends to flatten the liquid stream 41 (Fig. 10) along the planes 43 which intersects the axis of the jets, and the two pairs of converging jets respectively 115 spread the resulting flattened spray along this same plane but at opposite sides of the axis of the initial liquid stream. By projecting a tubular stream of air 42 around this liquid stream, I sheath the latter so as to prevent it from spreading before the converging air jets impact against it. Then, when the air-sheathed liquid stream is reached simultaneously by the four converging air jets, the 120 engagement of the tubular air stream by the 125 130

converging air jets causes air movements which assist in breaking the liquid stream into fine particles. Consequently, I can secure an exceedingly fine atomization and one in which 5 the liquid is distributed with a high degree of uniformity.

By partially rotating the member 22, which is easily turned by grasping the lugs 29 and 30 with the fingers, I can instantly change the 10 plane of the spray-flattening from the medial plane of the handle to one at right angles to that plane. Or, by halting the member 22 at any intermediate point in which the recesses 15 31 and 32 do not aline with the grooves 34 and 35, I can instantly render the converging ports inoperative, thereby securing merely the conical spray resulting from the uninterrupted action of the tubular air jet on the liquid stream.

20 By subdividing the air jets into pairs, I correspondingly reduce the velocity of each of these jets, being able to do this since the angular converging of each pair permits me to employ ports of comparatively large bores. 25 This reduction in air velocity cooperates with the above described atomizing action in increasing the effective uniformity of the spray, thereby entirely avoiding the formation of the above mentioned "pock marks". Moreover, I attain these long desired results without employing complicated mechanisms. By 30 unscrewing the collar 33, the member 22 can instantly be withdrawn to permit a cleaning of its ports and to afford access to the front 35 of the body member as shown in Fig. 5, and, if desired, members 22 with different sizes of ports or different angularities between the ports could readily be substituted for each other so as to secure corresponding variations 40 in the contour and size of the resulting and substantially fan-shaped spray.

However, while I have illustrated and described my invention in an embodiment having numerous highly desirable features, I do 45 not wish to be limited to the details of the construction and arrangement thus disclosed. Obviously, many modifications might be made without departing either from the spirit of my invention or from the appended 50 claims. Neither do I wish to be limited to the employment of my invention in a portable appliance of the socalled spray gun type, though it is highly suitable for such embodiments.

55 I claim as my invention:—

1. In a liquid spraying appliance, a nozzle for discharging liquid in a solid stream, and an air discharge member having two pairs of air ports, the ports of each pair being nearer to each other than to the ports of the other pair and all of the said ports being disposed for directing air substantially against a single point on the axis of the discharge stream of liquid, the air ports of both pairs being relatively close to a plane axial of the liquid

stream and the ports of each pair being symmetrically disposed with respect to the said plane.

2. In a spraying appliance, a body member, a collar carried thereby, a rotatable member 70 mounted between the collar and the body member, and means for projecting a stream of liquid through the rotatable member axially of the latter, and means for supplying compressed air behind the rotatable member, the 75 rotatable member having two pairs of ports extending from its side through its front and all directed towards a common point ahead of the rotatable member and on the axis thereof, the collar having a pair of channels aligning respectively with the rear ends of the said pairs of ports when the rotatable member is in a certain position so as to admit air from behind the said member to the said ports.

80 3. A spraying appliance as per claim 2, in which the rotatable member has a pair of forwardly directed projections through which the pairs of ports respectively extend, the said projections serving also as means whereby the 90 said member may be manually rotated.

4. A spraying appliance as per claim 2, in which the rotatable member has a pair of forwardly directed projections through which the pairs of ports respectively extend, the 95 said projections having forward faces approximately at right angles to the ports extending through these projections.

5. In a spraying appliance, a body member, a collar carried thereby, a rotatable member 100 mounted between the collar and the body member, and means for projecting a stream of liquid through the rotatable member axially of the latter, and means for supplying compressed air behind the rotatable member, the rotatable member having two pairs 105 of ports extending from its side through its front and all directed towards a common point ahead of the rotatable member and on the axis thereof, each pair of ports being relatively near each other and diametrically opposite the other pair, the collar having two pairs of diametrically opposite channels extending longitudinally thereof, the channels of either pair being adapted to supply air 110 from behind the rotatable member respectively to the two pairs of ports according as the rotatable member is in one or the other of two positions.

6. A spraying appliance as per claim 2 in 120 which the rotatable member and the collar have similarly tapered adjacent surfaces, in combination with spring-pressed plungers continuously urging the rotatable member forward to effect a closure between the said surfaces.

7. A device for producing a spray flattened along a given plane, including means for projecting a stream of liquid with its 130 axis in the said plane, means for projecting

a hollow stream of air coaxial with the liquid stream for preventing a spreading of the latter, and means for projecting against the aforesaid coaxial streams upon opposite sides 5 thereof two forwardly directed pairs of jets all directed toward a single point on the said axis, the jets of each pair being at acute angles to each other.

8. A device for producing a spray flattened along a given plane, including means 10 for projecting a stream of liquid with its axis in the said plane, means for projecting a hollow stream of air coaxial with the liquid stream and of greater velocity than the liquid stream so as to produce an air-sheathed 15 stream of liquid, and means for projecting a plurality of jets of air upon opposite sides of and toward a single point on the said axis along axes symmetrically disposed with respect to the said plane and all forwardly inclined to the aforesaid axis.

9. A device for producing a spray flattened along a given plane, including means 20 for projecting a stream of liquid with its axis in the said plane, means for projecting a hollow stream of air coaxial with the liquid stream so as to produce an air-sheathed liquid stream, and means for projecting liquid stream, and means for projecting 25 against a single point along the said axis a plurality of oppositely disposed air jets having their axes converging after the manner of the edges of a laterally flattened 30 pyramid which pyramid has its own axis disposed in the said plane and its greatest base length parallel to the said plane.

10. A liquid spraying appliance, comprising 35 a body, a nozzle for discharging liquid in a solid stream, a rotatable air discharge

member having two pairs of air ports, the 40 ports of each pair being nearer to each other than to the ports of the other pair and all of the said ports being disposed for directing air substantially against a single point on the axis of the discharged stream of liquid, and a supporting member carried by said body to rotatably support the air discharge member, said supporting member having a pair of channels alining respectively with the rear ends of the said pairs of ports when the air discharge member is in a certain position 45 so as to admit air from behind the said member to the said ports.

11. A liquid spraying appliance, comprising 50 a body, a nozzle for discharging liquid in a solid stream, a rotatable air discharge member having two pairs of air ports, the 55 ports of each pair being nearer to each other than to the ports of the other pair and all of the said ports being disposed for directing air substantially against a single point on 60 the axis of the discharged stream of liquid, the air ports being so disposed that the jet of air discharged through each thereof is in a common plane with the jet of air discharged 65 through an air port of the other pair, and a supporting member carried by said body to rotatably support the air discharge member, said supporting member having a pair of channels alining respectively with the rear 70 ends of the said pairs of ports when the air discharge member is in a certain position so as to admit air from behind the said member to the said ports.

Signed at Chicago, Illinois, October 6, 1924.

HARRY D. BINKS.
